CONNECTER FOR ELECTRIC CONDUCTORS

William C. Stevens, Milwaukee, Wis., assignor, by
mesne assignments, to Cutler-Hammer, Inc.,
Milwaukee, Wis., a corporation of Delaware

Application September 10, 1926, Serial No. 134,698
Renewed June 10, 1932

15 Claims. (Cl. 173—361)

This invention relates to improvements in connectors for electric conductors and more particularly to improvements in plug caps for separable attachment plugs.

5 An object of the invention is to provide a plug cap of simple and relatively inexpensive construction, which is nevertheless capable of withstanding more rough usage than such devices as heretofore constructed.

10 Another object is to provide a plug cap wherein the amount of insulating material is reduced to a minimum while providing increased protection for the current carrying elements.

15 Another object is to provide an improved and simplified mounting for the plug contacts and terminals.

Another object is to provide novel means for securing the several elements in assembled relation.

20 Other objects and advantages of the invention will hereinafter appear.

In the accompanying drawing I have illustrated certain embodiments of my invention which will now be described, it being understood that various changes in the details of construction thereof may be made without departing from the spirit and scope of my invention as defined in the appended claims.

25 In the drawing, Figure 1 is an enlarged vertical sectional view of a plug cap constructed in accordance with my invention;

30 Fig. 2 is a bottom plan view of the cap illustrated in Fig. 1.

Fig. 3 is a plan view of the base or disk to which the plug contacts are secured;

Fig. 4 is a vertical sectional view of a modified form of plug cap;

Fig. 5 is a vertical sectional view of a modified form of the plug cap illustrated in Fig. 4; and

Fig. 6 is a vertical sectional view of the insulating lining employed in the caps illustrated in Figs. 4 and 5.

35 Referring first to the device illustrated in Figs. 1 to 3 of the drawing the numeral 10 designates a metallic shell or casing adapted to receive and retain the insulating and current carrying elements of the plug cap. One end of shell 10 is provided with an opening 11 to permit passage of the lead-in wires or conductors and the opposite end of said shell is provided with an enlarged annular rim portion 12, forming an annular shoulder 12a.

40 A thin cup-shaped insulating lining 13 rests within shell 10, said lining extending to a point

substantially flush with said shoulder 12a, and being provided with a central opening 14 registering with opening 11. Said lining suitably insulates the inner surface of the metal shell.

45 A circular plate or disk 15 of insulating material, such as a canvas-reinforced synthetic resin composition, is adapted to seat upon shoulder 12a and against the lower edge of lining 13, said disk being adapted to support contact jacks 16, as hereinafter more fully described. A circular insulating collar or ring 17 is interposed between disk 15 and the outer end of rim 12. In practice collar 17 may be formed from a flat strip of fibrous insulating material of the required length to provide a split ring of the desired size. After inserting lining 13, disk 15 and collar 17 into shell 10, the outer edge (indicated in dotted lines at 18) of rim 12 is spun or bent over as indicated at 19. By the means aforescribed the interior surface of shell 10 is sufficiently covered with insulating material to protect all current carrying parts of the cap from engagement with the shell.

50 Contacts 16 are of usual construction, and are provided with terminal lugs or base portions 20. These lugs are provided with circular openings 21 and 22 adapted to register with openings 24 and 25 in disk 15. Suitable eyelets or rivets 23 provide for rigidly securing lugs 20 to base 15. Openings 22 provide clearance for the conductor securing terminal screws 24. Base 15 is provided with a suitable opening or perforation to permit passage of the conductors or wire terminals therethrough; whereas if desired any suitable form of strain relief (not shown) may be located within the plug cap. The contacts 16 are also provided with the usual knife edge or beveled tips 26 to facilitate insertion of the same into a plug base or receptacle. Openings 27 in the contacts provide means whereby the latter are frictionally interlocked with the contacts of the plug base.

55 Referring to Fig. 4, illustrating a modification of the plug cap shown in Figs. 1 to 3, and in which the aforescribed disk 15 and contacts 16 are employed, the numeral 30 designates a metallic shell of a form slightly different from that illustrated in Fig. 1. In this form a relatively thick insulating lining 31 is adapted to fit into the hemispherical end portion of the shell. Disk 15 is adapted to rest upon the outer end portion 32 of this lining. A ring 33 of insulation, similar to that shown at 17 in Fig. 1, likewise seats against disk 15. Flange 34 (indicated in dotted lines) is thereupon spun or pressed down as shown at 35 to rigidly secure the elements of the plug cap in their respective positions. The cap illus-

trated in Fig. 5 is similar to that of Fig. 4, except that the shell 36 is provided with an annular bead or corrugation 37 to facilitate manipulation of the plug cap. Shells 30 and 36 are provided with circular openings 11 as described in connection with Fig. 1, through which the conductors enter the cap. Lining 31 (Figs. 4, 5 and 6) is also provided with a registering opening 38 for a like purpose.

10 The insulating lining portions of the cap are preferably formed of a suitable tough, fibrous material, whereas the contact supporting disk is also formed of a tough or reinforced form of insulation. Moreover, in practice the lining 13 shown 15 in Fig. 1 may consist of paper or other inexpensive fibrous material. It will thus be apparent that plug caps of the character herein described are not liable to break when dropped or otherwise roughly handled. Similarly, the various parts 20 may be readily assembled to provide a strong and serviceable plug cap.

What I claim and desire to secure by Letters Patent is:

1. In an attachment plug, the combination with 25 a one-piece metallic shell, of a lining therefor composed of separate insulating sections, a perforated insulating disk or plate interposed between said sections, contact members rigidly secured to said disk, and means for securing said shell, lining and disk in assembled relationship to each other.

2. In an attachment plug, the combination with 30 a one-piece metallic shell, of a lining therefor composed of separate insulating sections, a perforated insulating disk or plate interposed between said sections, contact members rigidly secured to said disk, and means on said shell for securing said disk and said sections in assembled relation.

3. An attachment plug cap comprising a one-piece metallic shell, a sectional lining therefor, said lining comprising tough fibrous insulating material, a perforated base of insulating material interposed between the lining sections, a plurality 45 of combined contact blade and wiring terminal members carried by said base, and common means for securing the several parts in assembled relation, the wiring terminal portions of said members being accessible for wiring after complete assembly of the cap parts.

4. An attachment plug cap comprising a one-piece metallic cap body, a sheet insulation lining for said body secured within the latter, a relatively thin but relatively rigid member of sheet insulation arranged within said cap body in a plane spaced upwardly from the lower edge thereof and engaged on opposite faces thereof by said lining for support by the latter, and contact blades rigidly secured to said relatively rigid 55 member.

5. An attachment plug cap comprising a metallic cap body, a sheet insulation lining for said body secured within the latter, a relatively thin but relatively rigid member of sheet insulation arranged within said cap body and engaged with said lining for support by the latter, said member having an opening formed therein to provide a cord passage, and combined wiring terminal and contact blade members rigidly secured to the 65 outer face of said relatively rigid member, said wiring terminals being exposed and readily accessible in the assembled relation of said parts.

6. In an attachment plug cap, the combination with 70 a one-piece metallic shell of substantially cup-shape, an annular shoulder intermediate the

ends of said shell, an insulating member resting within said shell and having its outer edge substantially flush with said shoulder, an insulating disk adapted to seat against said shoulder, an insulating ring adapted to engage the opposite side of said disk to hold the latter in position and means for retaining said ring in assembled relation to said shell.

7. In an attachment plug cap, the combination with 75 a one-piece metallic shell of substantially cup-shape, an annular shoulder intermediate the ends of said shell, an insulating member resting within said shell and having its outer edge substantially flush with said shoulder, an insulating disk adapted to seat against said shoulder, an insulating ring adapted to engage the opposite side of said disk to hold the latter in position, and an annular inturned flange on said shell adapted to engage said ring.

8. In an attachment plug cap, the combination with 80 a one-piece metallic shell of substantially cup-shape, an annular shoulder intermediate the ends of said shell, an insulating member resting within said shell and having its outer edge substantially flush with said shoulder, an insulating disk adapted to seat against said shoulder, said shell, insulating member and disk having registering openings to permit passage of connecting wires, and a relatively thick insulating ring interposed between said disk and the outer end of said shell, the latter having an inturned annular flange 85 engaging said ring to hold the parts in assembled relation.

9. An attachment plug cap comprising a one-piece metallic shell, a lining therefor comprising a plurality of sections of sheet insulation, a relatively thin but relatively rigid member of sheet insulation engaged with and supported by said insulating lining said member having an opening formed therein to provide a cord passage, and a plurality of one-piece combined contact 90 blade and terminal members secured to said relatively rigid member of sheet insulation and exposed on the outer face of the latter.

10. An attachment plug cap comprising a metallic cap body, a sheet insulation lining for said body secured within the latter, a relatively thin but relatively rigid member of sheet insulation arranged within said cap and engaged with said lining for support by the latter, said cap body, sheet insulation lining and relatively rigid member each having an opening and said openings being aligned to provide a cord passage, and one-piece combined wiring terminal and contact blade members carried by said relatively rigid 95 member, the wiring terminal portions of said members being exposed and readily accessible in the assembled relation of said parts.

11. An attachment plug cap comprising a cup-shaped cap having interior walls formed of sheet insulation, a relatively rigid part of sheet insulation spanning the interior of said cap and engaged with the insulation walls of the latter for support thereby in a fixed position, contact blades fixed to said relatively rigid part and having wiring terminals on the exposed face of the latter, said cap having an annular wall projecting beyond said relatively rigid part and said wiring terminals to seat endwise against a complementary plug part, and said plug cap being formed to provide a passage for wires to be attached to said terminals.

12. An attachment plug cap comprising a cup-shaped cap having outer walls formed of sheet metal and inner walls formed of sheet insula- 95

tion, the latter being secured within the former, a relatively rigid part of sheet insulation with an opening therethrough spanning the interior of said cap and engaged with the walls of the latter for support thereby in a fixed position, and contact blades fixed to said relatively rigid part and having wiring terminals on the exposed face of the latter, said cap having an annular wall projecting beyond said relatively rigid part and said wiring terminals to seat endwise against a complementary plug part.

13. An attachment plug cap comprising a cup-shaped cap having interior walls of insulation, an insulating base spanning the interior of said cap and engaged with the insulation walls of the latter for support thereby in a fixed position, said base consisting of a flat substantially circular disk of relatively thin but relatively rigid sheet insulation, said disk having a central perforation providing a cord passage, a plurality of one-piece combined contact and wiring terminal members positioned on one face of said disk with the contact portions extending in parallel relation at substantially right angles to said face of the disk, rivets penetrating said disk and members at points adjacent to the contact portions thereof respectively to secure said members to said disk, binding screws carried by said one-piece members at points spaced from said rivets, said disk having other perforations to accommodate the shanks of said binding screws, and said cap having an annular wall projecting beyond said disk and said wiring terminals to seat against a complementary plug part.

35 14. An attachment plug cap comprising a sub-

stantially cup-shaped cap having interior annular shoulders of insulation definitely spaced from each other and from the opposite ends of said cap, an insulating base positioned between said annular shoulders and held thereby against longitudinal movement with respect to said cap, said base consisting of a flat substantially circular disk of relatively thin but relatively rigid sheet insulation, said disk having a central perforation providing a cord passage, a plurality of one-piece combined contact and wiring terminal members positioned on one face of said disk with the contact portions extending in parallel relation at substantially right angles to said face of the disk, rivets penetrating said disk and said members respectively to secure the latter to the former binding screws carried by said members, and said disk having other perforations to accommodate the shanks of said binding screws.

15 15. An attachment plug cap comprising a one-piece cup-shaped metallic shell having a cord opening therein, a lining of sheet insulation adapted to cover substantially the entire inner surface of said shell, a plurality of contact blades, means for supporting said blades within the shell with portions of said blades projecting from the shell, said means comprising a relatively thin but relatively rigid disk of sheet insulation to which said blades are secured, said disk having a cord opening registering with the opening first mentioned, and common means for securing said relatively rigid disk to said lining for support thereby and for securing the latter within said shell.
